ADJUSTABLE BOOK SUPPORT

Edward Newmeyer, Jr., Pittsburgh, Pa.

Application July 29, 1935, Serial No. 33,687

9 Claims. (Cl. 281—33)

This invention relates to adjustable book supports, and more particularly to supports attached to the book itself.

In order to adjust or change the adjustment of book supports of this type known heretofore so as to position a book at the desired angle to the horizontal, it has been necessary to turn the book around or to reach around it, because the adjustment could be made from the back of the book only. With large books, such as ledgers, it causes a considerable amount of trouble to do this, and as a result adjustable supports have not been favored, although there is a real need for a practical one. Furthermore, these book supports have been formed as a part of the back of the book, and consequently have not been suitable for use with loose-leaf ledgers and the like which do not have a back and in which the thickness of the book is varied from time to time as the number of sheets between the separate covers is varied.

It is among the objects of this invention to provide an adjustable book support of the type referred to above which is adjustable from in front of the book, which is adapted for use with a book of varying thickness, which can be made either as a permanent part of a book or as a detachable attachment therefor, and which is adapted to support a book at substantially any inclination to the horizontal.

The invention is illustrated in the accompanying drawings in which Fig. 1 is a perspective view of a loose-leaf book supported by my adjustable support; Fig. 2 a rear view of the book with the supporting arm in inoperative position; Fig. 3 an enlarged view, partly broken away, taken on the line III—III of Fig. 2; Fig. 4 a perspective view of a detachable book support; and Figs. 5, 6, and 7 side views partly broken away, of modified embodiments of the invention.

Referring to the first three figures of the drawings, the invention is shown used in conjunction with a loose-leaf book having two separate covers 1 and 2 and no back, such as a ledger. Back cover 1 is hinged at its rear edge in any suitable manner to a narrow binding member 3 from the inner face of which extend detachable binding posts 4 on which the perforated loose sheets 6 are mounted. Front cover 2 is likewise hinged to a binding member 7, of the same general outward appearance as binder 3, provided with holes 8 through which posts 4 slidably extend. The posts are normally locked in these holes by any well-known means, not shown.

Binder 3 is formed of a tubular member 9 pro-

vided in its rear side with an elongate opening 12 and closed at its ends by detachable metal caps 11, whereby a housing is formed. As shown in Figs. 2 and 3, a supporting arm 13 extends longitudinally of the tubular housing directly inside of opening 12, and is pivoted at its lower end in the lower end of the housing. This arm is adapted to be swung backwardly in a vertical plane until its free end engages the surface on which the book is resting, a rubber tip 14 preventing the end 10 of the arm from marring the surface.

To hold arm 13 behind the book at selective angles to the housing so as to permit the open book to be supported by the arm at any desired angle to the horizontal (Fig. 1), the pivoted end 15 of the arm is enlarged to form a segmental portion 16 having in its periphery ratchet teeth 17 engaged by a pawl 18 pivotally mounted in tube 9. The pawl is disengaged from the ratchet teeth preferably by depressing a rod 19 extending from 20 the pawl up through tube 9 and upper cap 11 where it is provided with a button 21. The pawl is normally held in engagement with the ratchet teeth by a spring 22 encircling a pin 23 in the top 25 of the housing and stressed between the rear side 25 of tube 9 and a collar 24 rigidly mounted on rod 19.

Although spring 22 might be made strong enough to so firmly hold the pawl in engagement with the ratchet teeth that the arm could not 30 accidentally swing out of the housing, it is preferred to positively lock the arm in the housing when the support is not in use by providing the free or upper end of the arm with a clip 26 which is engaged by a spring-biased latch 27 pivotally 35 mounted in tube 9. Rod 19 extends through a slot in one end of the latch and is provided with a second collar 28 that depresses the latch to disengage it from the clip at the same time that the rod disengages the pawl from the ratchet, where- 40 by the arm is free to swing backwardly out of the housing whenever button 21 is depressed.

The adjustable support described above may be used by standing up the book at the angle desired and then depressing button 21 to disengage latch 45 27 from clip 26, and pawl 18 from the ratchet. Supporting arm 13 is thus permitted to swing back until its rubber tip strikes the surface on which the book is resting. Button 21 is then released and the pawl again engages one of the 50 ratchet teeth, whereby the supporting arm is locked at the desired angle to the housing and the book is prevented from falling over backwards. Another convenient manner of utilizing this adjustable support is to lay the book on a 55

- surface and open it to the desired page. Button 21 is then depressed to release the supporting arm, and the far edge of the book is raised until the book is at the desired angle to the horizontal.
- 5 During this raising of the book the released supporting arm remains on the supporting surface. When the book has been pulled up to the desired angle the pawl is permitted to engage a ratchet tooth for locking the arm in that position relative 10 to the housing. The inclination of the book can be changed at any time by merely depressing button 21 to unlock arm 13, and then swinging the book up or down to the desired position.

An adjustable book support constructed in accordance with this invention is quickly operated from in front of the book, whereby it is unnecessary to reach around in back of the book or to turn the book around every time an adjustment is to be made. By mounting the support in one 15 of the binders of a loose-leaf book it does not prevent the thickness of the book from being varied by the insertion or removal of loose-leaf sheets. Furthermore, the book can be supported at substantially any angle to the horizontal, thereby permitting the most suitable inclination to be 20 obtained.

In Fig. 4 an adjustable book support is shown which is not built into a loose-leaf binder, but is a separate unit adapted to be detachably secured 25 to conventional loose-leaf binders. The operating mechanism, however, of this modification is the same as that described above. Attached to one side of housing 31 along its rear edge is a sheet metal flange 32 that is L-shape in cross 30 section, whereby a recess 33 is provided between it and the adjacent side of the housing. This recess is of a width suited to receive a loose-leaf binder of standard thickness so that the housing can be mounted on the outer side of the binder. 35 The housing and flange are provided with holes 34 through which the binder posts project and lock the unit on the binder. Small variations in thickness of different binders is taken care of by 40 the resiliency of flange 32. This detachable support can be applied to a book or ledger in frequent use, and removed therefrom when the book 45 is filed away with the expectation that it will not be used much in the future.

In the remaining three figures of the drawings 50 three different ways of locking the supporting arm in predetermined positions are illustrated. Any of these mechanisms can be built into a binder as in Fig. 2, or can be made into a detachable unit like that of Fig. 4.

55 In Fig. 5 the button-engaging spring is omitted, and a coil spring 36 is substituted therefor. This spring encircles rod 19 below latch 27 where it is compressed between a collar 37 rigidly mounted on the rod, and a bifurcated lug 38 struck out of 60 the side of the housing and bent inwardly at right angles thereto.

The rod and latch are omitted in the embodiment shown in Fig. 6, and the support is adjusted from the bottom of the housing instead of the top. 65 Ratchet teeth 17 on the lower end of the supporting arm are engaged by a vertically disposed pawl 41 pivoted in the housing and biased toward the teeth by a U-shape spring 42 compressed between the pawl and housing. The lower end of the pawl 70 projects through an opening 43 in the bottom of the housing where it forms a finger piece 44 for moving the pawl out of engagement with the ratchet teeth.

75 The lower end of the supporting arm in Fig. 7 is provided with gear teeth 46 that mesh with a

worm gear 47 formed on the lower end of a shaft 48. The shaft extends longitudinally of the housing with its ends journaled in lugs 49 struck out of the side of the housing. The upper end of the shaft does not project out of the housing, 5 but is provided with a squared portion 51 for receiving a key (not shown) that can be inserted through an opening 52 in the top of the housing. The supporting arm is lowered or raised by turning shaft 48.

According to the provisions of the patent statutes, I have explained the principle and mode of operation of my invention, and have illustrated and described what I now consider to be its best embodiments. However, I desire to have it understood that, within the scope of the appended claims, the invention may be practiced otherwise than as specifically illustrated and described.

I claim:

1. In combination with a book, a housing connected to the rear portion thereof, an arm pivoted at one end in said housing for swinging in a substantially vertical plane behind the book, and means operable from the front of the book for holding said arm at selective angles to the housing whereby to support the book at a desired angle to the horizontal.

2. In combination, with a book, a housing connected to the rear portion thereof, an arm pivoted at one end in said housing for swinging in a substantially vertical plane behind the book, and pawl and ratchet means for holding said arm at selective angles to the housing whereby to support the book at a desired angle to the horizontal.

3. In combination with a book, a housing connected to the rear portion thereof, an arm pivoted at one end in the lower end of said housing for swinging in a substantially vertical plane behind the book, the pivoted end of said arm being provided with a curved portion having notches 40 in its periphery, a pawl mounted in said housing and normally engaging said arm in said notches, and means for releasing said pawl from the notches to permit said arm to be positioned at selective predetermined angles to the housing 45 whereby to support the book at a desired angle to the horizontal.

4. In combination with a book, a housing connected to the rear portion thereof, an arm pivoted at one end in the lower end of said housing 50 for swinging in a substantially vertical plane behind the book, the pivoted end of said arm being provided with a curved portion having notches in its periphery, a pawl mounted in said housing and normally engaging said arm in said 55 notches, and means projecting from the upper end of the housing for releasing said pawl from the notches to permit said arm to be positioned at selective predetermined angles to the housing whereby to support the book at a desired angle 60 to the horizontal.

5. In combination with a book, a housing connected to the rear portion thereof, an arm pivoted at one end in the lower end of said housing 65 for swinging in a substantially vertical plane behind the book, the pivoted end of said arm being provided with a curved portion having notches in its periphery, a pawl mounted in said housing and normally engaging said arm in said 70 notches, and means projecting from the lower end of the housing for releasing said pawl from the notches to permit said arm to be positioned at selective predetermined angles to the housing whereby to support the book at a desired angle 75 to the horizontal.

6. In combination with a book, a housing connected to the rear portion thereof, an arm pivoted at one end in the lower end of said housing for swinging in a substantially vertical plane behind the book, the pivoted end of said arm having a curved portion provided at its periphery with a plurality of gear teeth, a worm gear journaled in said housing and meshing with said teeth, and means projecting from the upper end of the housing for turning the worm gear to permit said arm to be moved to selected angles to the housing whereby to support the book at a desired angle to the horizontal.
- 5 7. In combination with a book, a housing connected to the rear of one only of the covers of the book, an arm pivoted at one end in the lower end of said housing for swinging in a substantially vertical plane behind the book, the opposite end of the arm being free, means operable from the front of the book for holding said arm at selective angles to the housing whereby to support the book at a desired angle to the horizontal, and means for locking said free end of the arm in the housing.
- 10 8. In combination with a book, a housing connected to the rear of one only of the covers of the book, an arm pivoted at one end in the lower end of said housing for swinging in a substantially vertical plane behind the book, the opposite end of the arm being free, means operable from the front of the book for holding said arm at selective angles to the housing whereby to support the book at a desired angle to the horizontal, and means for locking said free end of the arm.
- 15 9. A book support comprising a housing adapted to be attached to the rear of a book cover, an arm pivoted at one end in the lower end of said housing for swinging in a substantially vertical plane behind the book, and means engaging the pivoted end of the arm and operable from one end of the housing for holding said arm at selective angles to the housing whereby to support the book at a desired angle to the horizontal.
- 20
